UNITED STATES PATENT OFFICE.

ROBERT J. MONTGOMERY, OF CHICAGO, ILLINOIS, ASSIGNOR TO SANITAX BRUSH COMPANY, A CORPORATION OF ILLINOIS.

BRUSH AND PROCESS OF MAKING SAME.

1,370,343.

Specification of Letters Patent.

Patented Mar. 1, 1921.

Application filed July 13, 1918. Serial No. 244,682.

To all whom it may concern:

Be it known that I, ROBERT J. MONTGOMERY, a citizen of the United States, residing at Chicago, in the county of Cook and State 5 of Illinois, have invented certain new and useful Improvements in Brushes and Processes of Making Same, of which the following is a specification.

My invention is an improved brush. The 10 invention relates to the attachment of the bristles or hairs to the base of a brush and is applicable to brushes designed for various uses. I have illustrated my invention in connection with an ordinary hair brush, in 15 which article it has certain advantages over prevailing methods and forms of construction.

The nature of my invention will clearly appear from the following description and 20 claim taken in connection with the accompanying drawings forming part of this application, in which drawings:

Figure 1 is a fragmentary view showing 25 in section part of the metal base of a brush. This view shows one socket in the brush base with a tuft of bristles and an anchor above the socket and ready to be inserted therein.

Fig. 2 is a view similar to Fig. 1 but viewing 30 the structure at 90 degrees from the viewpoint in Fig. 1, and showing the anchor and bristles inserted in the socket but not secured therein.

Fig. 3 is a sectional view similar to Figs. 1 and 2 and shows one socket with the 35 bristles in place and the operation of attaching them completed.

Fig. 4 is a view similar to Fig. 3 showing a modified form of construction.

Fig. 5 is a fragmentary view looking 40 directly at the metal base of the brush and exhibiting one socket of the form shown in Figs. 1 to 3.

Fig. 6 is a detailed view of one of the anchors.

Fig. 7 is a side view of a completed brush 45 embodying the form of construction illustrated in Figs. 1 to 3.

Fig. 8 is a modified form of construction wherein no holding anchor is used.

50 In Figs. 9 to 16 I have illustrated mechanism for carrying out the operations illustrated in the preceding views. Fig. 9 represents the machine with the anchor cutting die drawn to its outer position, the needle which forces the anchors and bristles into

the sockets in its upper position and the swaging anvil in its lower position. In Fig. 10 the die for cutting the anchors is shown in its inner position, having just completed the cutting of an anchor and having placed 60 the same in position below the needle. In Fig. 11 the needle has been moved to its lower position, forcing the anchor and bristles into the socket. Fig. 12 is a fragmentary view showing one of the sockets 65 and part of the machine, an anchor and bristles having been placed in the socket preparatory to swaging the edge of the socket. In Fig. 13 the socket is shown swaged inwardly at its upper edge to retain the bristles. Fig. 14 is a view similar 70 to Fig. 13, but at an angle of ninety degrees from the position shown in Fig. 13. Fig. 15 is a view similar to Fig. 11, simply showing the needle partially raised. Fig. 16 is a 75 cross-sectional view through the anchor, socket and bristles.

The metal base 1 of the brush in the form of construction illustrated in Figs. 1, 2, 3 and 7 is provided with a plurality of projecting bosses 2, one boss for each tuft of bristles. These bosses are preferably, though, of course, not necessarily cylindrical in form. The bosses are hollow, being merely cylindrical shells open at their outer 85 ends, thus forming the sockets wherein the bristles are attached to the base. In Fig. 1 I have shown one of these sockets in the form in which it is originally prepared and in the same figure have shown above the 90 socket a tuft of bristles 3 with an anchor 4 pressed down upon the middle of the tuft, the anchor 4 being shown in perspective in Fig. 6. The next stage in the operation of attaching the bristles is illustrated in Fig. 2 95 where the anchor 4 has been thrust downwardly into the socket 5, thus folding the bristles midway between their ends and carrying the folded part of the tuft into the socket, the anchor in the assembled position 100 overlying the central folded part of the bristles. The next stage in the process of attaching the bristles is illustrated in Fig. 3 and consists in swaging or otherwise forcing the metal at the mouth or edge of the socket 105 inwardly, as illustrated at 7, the metal being thrust inwardly sufficiently to constrict the mouth of the socket to an extent sufficient to prevent withdrawal of the anchor and bristles. The inward swaging or contrac- 110

tion of the walls of the socket may have the effect of imposing pressure directly upon the edges of the anchor to prevent removal of the bristles. In practice, however, I have 5 preferred to rely principally upon the constriction of the mouth of the socket to a diameter less than the width of the anchors, and this constriction may be carried to such a point as to compress the bristles, thereby 10 sealing the sockets against entrance of water or other liquid used upon the brush.

While the form of construction above described in which the sockets consist of hollow cylindrical bosses projecting from the 15 metal base is the form of my invention which I at present prefer, it will be obvious that the invention is not necessarily restricted to the construction of the sockets in this particular form. As illustrated in Fig. 4, the 20 sockets may consist simply of cylindrical depressions in a flat metal base. When so constructed a somewhat different form of tool and somewhat different manipulation will be necessary for the purpose of contracting 25 the outer edges or mouths of the sockets to prevent withdrawal of the anchors and bristles. In Fig. 4 I have shown the constriction of the socket as effected by depressing the metal around the socket at 8 and deflecting the displaced metal inwardly to 30 form an inwardly projecting ridge at 9, the mouth of the socket thus being reduced to a diameter less than the width of the anchor.

It will be noted that while the anchor is 35 being forced with the folded tuft into the socket, the close fit of the lower edge of the anchor within the socket and the concavity of its lower edge help hold the bristles of the tuft together and lessen the likelihood of 40 their escape around the edge of the anchor into the space between it and the adjacent wall of the socket, as would be the case were the fit loose and the lower edge straight. In this way a maximum number of bristles of 45 each tuft are folded and held at the bottom of the socket.

The process forming part of my invention is simple and economical in practice, the resulting brush is free from wires and the 50 metal base is free from such irregularities of form as would lend themselves with the wires to the accumulation of objectionable foreign matter. Furthermore, the base of the brush can be provided with cleansing 55 perforations between the bosses, as illustrated at 10 in Fig. 5.

In Fig. 8 I have shown in cross-section one socket of a brush in which the bristles are held by direct pressure of the constricted 60 mouth of the socket and without the use of an anchor. The process of attaching the bristles without anchors is similar to the method followed when anchors are used, except for the fact that the bristles are folded 65 and the folded part forced into the socket

by direct pressure of a tool or part of a machine instead of by pressure upon an anchor directly contacting with the bristles. After the folded part of the tuft of bristles has been forced into the socket the tool or 70 mechanism used for that purpose is withdrawn and the mouth of the socket is constricted as illustrated. The constricted mouth of the socket holds the bristles in place both by direct pressure upon the 75 bristles at the point where the edge of the socket is constricted upon them, and also by the enlargement resulting from folding the bristles, the fold of the bristles lying within the socket being of greater diameter 80 than the tuft at a distance from the fold where the bristles lie parallel.

Referring now to a form of mechanism which I have found suitable for carrying out my process, I have found that machines 85 similar in their general construction to those heretofore used for attaching bristles by means of anchors may be used, it being necessary, however, to modify the construction of these machines somewhat and to introduce some new features in order to effect those operations which do not form part 90 of previous processes.

Referring to Figs. 9 to 16, the mechanism illustrated comprises generally a stationary 95 head 20, a stationary table 21 and an anvil 22 provided with connections, not illustrated, for intermittently reciprocating the same in a vertical direction. I have not illustrated the power mechanism and connections for 100 actuating these parts, as they may be of any convenient construction and form no part of the invention claimed herein, which is restricted to the article and the process of 105 making the same.

The anchors are formed from a strip of metal 23 which is fed through a slot in the head 20, the slot extending at right angles to the plane of the drawing. Suitable means, not illustrated, are provided for intermittently feeding the strip 23 and for synchronizing the feeding of the metal strip with the other operations performed by the mechanism. A die 24 operating in a slot 25 extending at right angles to the slot in the 110 head 20 through which the metal strip 23 is fed is provided for the purpose of cutting the anchors from the metal strip, the cross section of the die and of the slot in which it moves being of the required shape of the anchors. Extending vertically through the machine intersecting the slot in which the die operates is a slot 26 in which a vertically reciprocating needle 27 operates. Beneath the table 21 is a combined guide and swaging member 28, the lower part of which is shown upon a larger scale in Figs. 12 to 14 inclusive. This guide and swaging member is provided with a central aperture 29 directly beneath and registering with the 115 120 125 130

slot 26 in which the needle 27 operates. This central aperture in the member 28 is of substantially the same size as the sockets in the brush base and the lower part of the aperture 29 is flared outwardly, as indicated at 30, to embrace the upper edge of the bosses 2 upon the brush base 1, which, in the operation of the machine is mounted upon the anvil 22, as illustrated, and accurately positioned beneath the member 28 with the upper edge of the boss projecting into the flared lower end of the aperture in that member. Suitable mechanism, not illustrated, and of a character well known in the art, is provided for feeding tufts of bristles to a position upon the table 21 beneath the slot 26. In Fig. 10 I have shown a tuft of bristles 31 in the position referred to and ready to be operated upon by the mechanism.

The sequence of operations in using the machine is as follows:

At the start the needle 27 is drawn to its upper position, the die 24 is withdrawn to its outer position and the anvil 22 is moved to its extreme lower position to permit the brush to be positioned with one of its sockets beneath the opening in the member 28. The anvil is then raised to an intermediate position illustrated in Figs. 9, 10 and 12, in which position the socket is held in registry with the opening in the member 28. The die 24 is then moved inwardly to the position illustrated in Fig. 10, thereby cutting an anchor 4 from the strip 23 and positioning the anchor in the slot 26 directly beneath the needle 27. The die 24 is then moved outwardly, as shown in Fig. 11, and the needle 27 is forced downwardly. As the needle moves downwardly it forces the anchor 4 downwardly in the slot 26 and when the anchor contacts with the center of the tuft of bristles 31 the bristles are folded and carried downwardly through the aperture 29 in the member 28 and in the lowermost part of its movement the needle forces the anchor 4 overlying the fold of the bristles into the socket 5 in the base of the brush, this latter position of the mechanism, bristles and anchor being illustrated in Fig. 11. As soon as the anchor and bristles have been inserted in the socket, as shown in Figs. 11 and 12,

the needle is withdrawn and the anvil 22 is raised to its upper position illustrated in Figs. 13 to 15, thus forcing the edge of the boss 2 into the converging mouth of the opening in the member 28, thereby swaging the edges of the socket inwardly, as illustrated at 7 in Figs. 13 and 14, which inward swaging has the effect of securely holding the anchor and bristles in place as hereinabove described.

When the bristles are attached, as illustrated in Fig. 8, without the use of an anchor, the procedure and apparatus may be similar to that above described except for the omission of the anchor cutting die, and the provision of a needle having its lower end of sufficient width to engage the bristles 31 and force them into the socket. After the withdrawal of the needle the socket may be contracted at its upper edge in the way and by means similar to that above described in connection with the anchor form of construction.

What I claim is:

An article of the class described comprising a one-piece metal back having a plurality of sockets integral therewith and a plurality of tufts of bristles, each socket having a closed surrounding wall and a closed inner end wall, each tuft of bristles being folded intermediate its ends and having its folded part within one of said sockets engaging its peripheral wall and its inner end wall, a flat metal anchor for each tuft of bristles closely fitting against opposite portions of said peripheral wall and lying within the fold of bristles, said anchors pressing the bristles compactly and firmly against the end walls of the sockets and being of such length that their outer ends lie inward of the outer ends of the sockets, and the walls of said sockets exerting pressure directly upon the edges of the anchors to prevent removal of the bristles and engaging the bristles to compress them and thus seal the socket against the entrance of water or other liquid used upon the brush.

In testimony whereof I have subscribed my name.

ROBERT J. MONTGOMERY.
